RADIO APPARATUS

Leslie A. Gould, Bridgeport, Conn., assignor, by direct and mesne assignments, to Columbia Phonograph Company, Inc., Bridgeport, Conn., a corporation of New York

Application April 23, 1925, Serial No. 25,253

8 Claims. (Cl. 250—40)

This invention relates to radio receiving mechanism, and particularly to a control device therefor, and has for an object to provide a control for the tuning device or devices of a receiving set which will greatly simplify the operation of tuning the set for different stations.

It is also an object of the invention to provide a control for the tuning device or devices in which the dials for the condensers or variometers are eliminated, and in which the tuning devices may be adjusted from a distance and through the medium of a single control device connected with the set by a flexible connection.

It is a further object of the invention to provide a means for adjusting the device or devices to perform the tuning operations which will not cause the set to squeal or howl as it very often does when the dials are twirled or operated too rapidly in the operation of tuning, and it will thus prevent the set from sending out radio frequency oscillations to interfere with neighboring sets.

With the foregoing and other objects in view, I have devised a control mechanism one embodiment of which is illustrated in the accompanying drawings forming a part of this specification, similar reference characters being employed throughout the various figures to indicate corresponding elements. In these drawings,

Fig. 1 is a diagrammatic view of a radio receiving set indicating in outline how my improved control and adjusting device may be applied thereto.

Fig. 2 is a front view of the cabinet which may be used to house a set controlled by my improved mechanism.

Fig. 3 is a detail of a portion of one form of an indicating device.

Fig. 4 is a top plan view of the cabinet for a receiving set showing one form of my improved controlling mechanism mounted therein, the tubes, coils and other devices of the set being omitted.

Fig. 5 is a front elevation of the arrangement shown in Fig. 4.

Fig. 6 is a longitudinal section through one form of a remote control device.

Fig. 7 is a longitudinal section substantially on line 7—7 of Fig. 6.

Fig. 8 is a longitudinal section of the control device substantially on line 8—8 of Fig. 6 and indicating diagrammatically a control for the first radio frequency tube, and

Fig. 9 is a transverse section through the remote control substantially on line 9—9 of Fig. 6.

Referring to Fig. 1, I have shown in this figure a wiring diagram for merely one type of radio receiving set, it being understood that this particular layout is shown merely for the purpose of illustrating my invention, and that my invention may be applied to all types of receiving sets. In this set a pair of audio frequency transformer coils are shown at T₁ and T₂, and at R₁, R₂ and R₃ are shown radio frequency transformers with variable condensers C₁, C₂ and C₃ connected across the secondaries of these transformers, and the sockets for the various tubes are shown at M₁, M₂, M₃, M₄ and M₅. In the embodiment illustrated there is connected to the shafts S₁, S₂ and S₃ carrying the movable plates of these condensers worm gears 10 meshing with worms 11 mounted on shaft sections 12 connected to a worm gear 13 which meshes with a worm 14 on the shaft 15 of an electric motor 16. The shaft sections 12 may be a single continuous shaft but I prefer to provide a short section for each tuning device and then connect the sections together by detachable couplings 17, these couplings in the present device being short collars clamped to the adjacent ends of the shaft sections by set screws 18. By this arrangement the tuning devices, either variable condensers or variometers, may be mounted in separate boxes or containers 19 with the shaft section 13 mounted therein and having driving connection with the movable element of the tuning device through the worm 11 and gear 10, so that each tuning device is a separate and distinct unit which may be mounted as a complete assembly or unit in the cabinet, and by merely duplicating these units and connecting the shaft sections together as many may be used as found desirable or required for the particular layout used. It will be apparent that all of these condensers or variometers will be adjusted by the motor 16.

This motor is also mounted within the set cabinet, but it is preferably enclosed in a lead cabinet or box 20 to prevent interference of the motor with the other devices in the cabinet, and the motor should be mounted on a rubber or fibre base 21 to absorb vibration and reduce the noise of operation. The motor shown is a shunt wound motor, the armature leads being shown at 22 and 23 and the field leads at 24 and 25. This motor is controlled by a remote control device, shown more in detail in Figs. 6 to 9, which is adapted to be held in the hand of the operator and at any convenient distance from the cabinet desired. This control device is connected with the motor and any other device with which it is to

be operated by flexible leads in a cord 26. In the layout illustrated this control comprises an insulating block 27 made in two sections, the upper one of which carries four stationary contacts 28 cross connected as indicated in Fig. 4, and mounted to slide between these contacts is a pair of slidable contacts 29 connected to a button 30 exposed on the outside of the control device, so that these contacts may be slid back and forth 10 to engage either the outer or inner pair of contacts 28 and control the operation of the motor, to which they are connected by the lead wires 31, through the battery 32 as indicated. In other words, this switch provides a reversing switch 15 which will operate the motor in either direction depending upon which pair of contacts 28 the slidable contacts 29 engage. Of course, other forms of switches may be used to carry out this function.

20 Mounted in the field circuit of the motor is a magnet coil 33 adjacent the pivoted armature 34 carrying a brake pad 35 adapted to engage the rim of a brake disc 36 mounted on the motor shaft 15, and a spring 37 tends to press this 25 brake pad against the disc. Thus when the circuit through the motor is closed the magnet 33 is energized and will move the pad away from the brake disc and allow the motor shaft to turn freely, and immediately the circuit through the 30 motor is broken the spring 37 will press the pad against the disc and quickly stop the motor. Thus when the desired adjustment is secured and the circuit broken the momentum of the motor will not spoil the adjustment. A condenser 39 is connected across the field coils of the motor to prevent it sending out radio frequency oscillations should the commutator and brushes get to 35 sparking in operation.

Also mounted on the control device 27 is a 40 control for the filament of the first radio frequency tube 38, so that there is also provided a remote control for controlling the volume of the sound produced. In the present embodiment there is mounted on the under side of the lower 45 section of the block 27 a pair of spaced resistance wires 39 connected by leads 40 in the cord 26 to the filament 41 of the first radio frequency tube and also the A-battery 42. These resistance wires are bridged by a slidable contact 43 which may 50 be adjusted longitudinally of these wires by means of a button 44 projecting through a slot in the cover plate 45 where it is accessible for operation on the other side of the control block from the control button 30 for the motor. Thus 55 it will be apparent that on the control device 27 which may be held in the hand of the operator at any desired distance from the set or receiving mechanism is a control for the motor which operates the tuning device or devices, and also a 60 control device for varying the volume of the sound produced.

It is desired that there be some indicator to 65 indicate to what stations the set is tuned. This indicator may assume various forms but in the present construction the front wall 46 of the cabinet is provided with an elongated opening 47 closed by a translucent member 48, such as ground glass, mounted in a suitable frame 49 secured over this opening as by screws 50. Connected to one of the movable shafts S1, S2, or S3, in the present case the central shaft S2, is a movable device for projecting a beam of light on the rear of this translucent window so that it is 70 visible from the front of the cabinet. In the 75 present case a small box or container 51 is

mounted on a shaft 52 of a gear 53, which gear meshes with a pinion 54 on the shaft S2. The box 51 is adjustable up and down on the shaft 52 so that it may be adapted to cabinets of different heights. Mounted in the box 51 is an electric light bulb 55 connected to any suitable source of power, such as the A-battery by a lead 56, the other terminal of the lamp being grounded. In the front end of the wall of the box 51 is a vertical slot so that a narrow beam of light will be 10 thrown from the light on the window 48 as indicated at 58, in Fig. 2. Because the shaft S2 is adapted to be adjusted more than a half revolution the pinion 54 is made smaller than the gear 53 so that turning movement of the box 51 is not 15 as great as the shaft S2 although it is proportionate thereto. Therefore, the shaft S2 may be turned to give maximum adjustment without throwing the beam of light off the window 48. The designation for the different stations may be 20 marked on the glass window if desired, as indicated in Fig. 2. Instead of swinging the lamp it will be obvious a mirror may be mounted to swing and arranged to project a beam of light on the window.

It is believed the operation will be obvious from the foregoing description. As the control device 27 may be held in the hand and is connected to the cabinet by a flexible cord 26 the operator may be stationed at any point desired and at any distance depending upon the length of the cord used. By merely operating the switch button 30 he may run the motor 16 either forwardly or backwardly as desired to adjust the tuning devices C1, C2, and C3 in either direction to tune in with any 35 station desired. Because of the large reduction in the driving ratio between the motor and the shafts S1, S2 and S3 through the medium of the worm gear drives the adjustment of these shafts 40 may be made very slow so that there is no squealing or howling of the set. As the shafts are adjusted the box 51 will be shifted a corresponding amount to swing the beam of light along the window 48 and the operator, if stationed at the front of the cabinet, may watch the movement 45 of this beam of light and determine thereby with what broadcasting station the set is tuned. Immediately the set is tuned in with any station desired and the station comes in with the desired clearness the motor circuit may be broken by 50 means of the button 30 and the motor will be immediately stopped by the brake mechanism as above described, and thus the adjustments may be stopped immediately at any point desired. As 55 pointed out above there is also a remote control of the volume of sound through the button 44 on the other side of the control block 27. If desired, the top wall of the cabinet may be made of insulating material such as bakelite and the binding posts for various electrical connections 60 mounted thereon.

It will thus be apparent that I have provided a simple and easily operated remote control for tuning the set to any station desired and also for 65 controlling the volume. Furthermore, this control eliminates all dials on the front panel of the cabinet and there is no chance of the operator twirling the dials and causing the set to squeal or howl as in the ordinary method of tuning. It will 70 also be obvious that as the control device is connected to the set through a flexible connection it is portable so that the operator may sit in one part of the room away from the cabinet, or may take it to a table at which he is sitting, or the 75

control may be given to an invalid in bed so that the set may be tuned to any station desired and controlled without the operator leaving any of these positions.

5 Having thus set forth the nature of my invention, what I claim is:

1. The combination with a radio receiving mechanism including a plurality of tuning devices comprising separate independent units having adjustable elements, a rotatable shaft for each device, a driving connection from the shafts to the respective elements, detachable adjustable connections between the shafts, a motor having rotatable driving connection with the shafts, and 10 a remote control means for the motor.

2. The combination with a radio receiving mechanism including a tuning device having a movable element, a panel having an opening covered with a translucent material, a lamp connected with said element to move in certain timing relation therewith and arranged to throw a beam of light on said translucent material, a motor, a driving connection from the motor to the movable element, and means for controlling 15 the motor to adjust the element.

3. The combination with a radio receiving mechanism including a tuning device having a movable element, a panel having a translucent window, means for throwing a beam of light on 20 said window and connected to move in certain timing relation with said element, power means for adjusting said element, and control means for the power means.

4. The combination with a radio receiving mechanism including a tuning device having a movable element, a panel having a translucent window, means for throwing a beam of light on 25 said window and connected to move in certain timing relation with said element, an electric motor, a driving connection from the motor to the element, and a re-

mote control for the motor having a flexible connection therewith.

5. In combination with a radio receiving mechanism including a tuning device having a movable element, a panel having a translucent window, means for throwing a beam of light on 5 said window and connected to move in certain timed relation with said element, and means for adjusting said element.

6. The combination with a radio receiving 10 mechanism including a plurality of tuning devices having rotatable adjustable elements, rotatable means for operating said devices, there being a detachable rotatable driving connection from said means to each of the respective elements, a motor for driving said means and means remote from said receiving mechanism for controlling the operation of the motor.

7. In combination with a radio receiving mechanism including a tuning device having a movable 15 element, a panel having an opening, a translucent member in the rear of said opening, a lamp member, one of said members connected with said element to move in certain timed relation therewith to indicate through said opening the position of said element, a motor, driving connection from the motor to the element, and means for controlling the motor to adjust the element.

8. In combination with a radio receiving mechanism including a tuning device having a movable 20 element, a panel having an opening therein, a translucent indication member in the rear of said opening, a light member for throwing a beam of light on said indicator member, one of said members connected to move in certain timed relation 25 with said element, and means for adjusting said element, said last means including a motor and means remote therefrom and connected thereto by flexible cable for controlling the movement 30 thereof.

LESLIE A. GOULD.
